UNITED STATES PATENT OFFICE.

JAMES C. FRENCH, OF KENOSHA, WISCONSIN, ASSIGNOR TO FREDERICK C. AUSTIN, OF CHICAGO, ILLINOIS.

WHEEL-EXCAVATOR.

1,215,791.

Specification of Letters Patent. Patented Feb. 13, 1917.

Application filed March 22, 1915. Serial No. 16,304.

To all whom it may concern:

Be it known that I, JAMES C. FRENCH, a citizen of the United States of America, and resident of Kenosha, Kenosha county, Wisconsin, (510 Exchange street,) have invented a certain new and useful Improvement in 5 Wheel-Excavators, of which the following is a specification.

My invention relates to excavators of that 10 kind in which a series of digging buckets are mounted on a rotary ring or spokeless wheel and thereby arranged to cut a trench or ditch as the machine moves slowly forward.

15. The principal object of my invention is to provide an excavator of this general character in which the buckets are provided with pivoted rear end gates, and in which the said gates are held in closed position by 20 latches or locking devices suitably mounted on the said ring or wheel, the said devices being automatically operated to open the gates when the buckets arrive at the point of discharge.

25. It is also an object to provide certain details and features of construction and combinations tending to increase the general efficiency and desirability of an excavator of this particular character.

30. To these and other useful ends my invention consists in matters hereinafter set forth and claimed.

In the accompanying drawings Figure 1 is 35 a side elevation of that portion of the excavator to which my invention relates, showing a rotary ring or spokeless wheel having digging buckets embodying the principles of my invention, and showing the same in operating position.

40. Fig. 2 is an enlarged detail section on line 2-2 in Fig. 1.

Fig. 3 is an enlarged plan view of the upper portion of the structure shown in Fig. 1, showing the cleaners for scraping the 45 contents from the buckets.

Fig. 4 is an enlarged side elevation of one of the said buckets, showing the pivoted gate thereof in section and in closed position in full lines, and showing said gate open 50 in dotted lines.

As thus illustrated, my invention comprises a frame A of any suitable character adapted to support the rotary ring or spokeless wheel B therein, being provided with 55 rollers b which engage the inner edge of the

ring for this purpose. Said ring is preferably composed of two outer angle iron sections C, as shown in Fig. 2, and an inner T-iron section D which is provided with gear teeth d at each side of the inner edge thereof. The rollers b are flanged to receive the inner edge of the section D, the teeth d being flush with said edge to prevent their engagement with said rollers, whereby the ring will rotate smoothly thereon about a horizontal axis extending below the frame. The driving shaft E is suitably mounted in bearings on the frame A and is provided with a double pinion F having two rows of teeth f which are spaced apart to engage the teeth d on the ring. With this formation, mud and dirt between the teeth d is easily pushed out by the teeth f during the rotation of the ring, inasmuch as the spaces between the teeth d are open at top and bottom thereof. The shaft E is driven by a sprocket chain connector e, the latter being operated in any suitable or desired manner. The scrapers G are suitably supported on the frame A and are bent inward, as shown in Fig. 3, to engage the side surfaces of the angle iron sections C, being arranged to throw the dirt outward and upon the laterally projecting spouts or sloping boards H at opposite sides of the wheel.

The buckets I are rigidly secured by their central walls i between the angle iron sections C, as shown in Fig. 2, and are disposed at the intervals around the perimeter of the wheel. Each bucket is open at its sides, and to prevent the dirt from falling out while the buckets are ascending from the ground a guard or housing J is arranged on the frame A in position to enclose the buckets while they are passing from the ground to the point of discharge at the top of the wheel.

The rear end of each bucket is provided with a swinging gate K pivoted at k to the heel of the bucket, each gate being slotted at L to receive the flange composed of the outer webs of the angle iron sections C of the said ring or spokeless wheel. At the end of this slot L inner and outer lugs l are provided. A latch or locking device M is pivoted at m between the said outer flanges of the wheel, immediately behind the bucket, and in position to pass through the slot L and engage the two lugs l when the gates swing shut. Each catch or locking device M is provided with a laterally projecting lug 100

105 of the wheel, immediately behind the bucket, and in position to pass through the slot L and engage the two lugs l when the gates swing shut. Each catch or locking device M is provided with a laterally projecting lug 110

N which engages a suitable portion or means on one of the cleaners G, thereby causing the latch M to tilt into the position shown in dotted lines in Fig. 4, thus unlocking the 5 gate. A stop O on the wheel limits this tilting movement of the latch M, and each latch or locking device remains in this position until the gate of its allotted bucket slams shut while moving downward after 10 discharging its load. This closing movement of the gate K causes the inner lug l to strike the latch M in a manner which causes the latter to swing into locking position, thus bringing the outer hook P of the 15 latch into position to engage the outer lug l, and thereby locking the gate in closed position to hold the next load against falling out until the bucket again reaches the dumping position. In this way, and while the 20 buckets are traveling through the ground, the pivoted gates K are positively locked in closed position. The cleaners G are shaped to scrape the inner surfaces of the buckets, as they pass through the buckets, and are 25 provided with means to automatically unlock the said pivoted gates. This permits the two cleaners to pass out of the rear ends of the gates, by relative movement between the buckets and cleaners, it being understood 30 that the said cleaners stand still while the buckets are moving forward. The practical effect, however, is correctly described by stating that the cleaners pass through the buckets to scrape out the dirt, this being 35 particularly necessary and desirable when the machine is working in clay or other sticky soil.

Any suitable means can be employed for supporting the frame A, as by mounting the 40 sprocket shaft Q on the rear end of the body frame of the machine. Also, any suitable means can be employed for swinging the frame A upward to bring the ring or wheel above ground. In addition, it will be 45 understood that any other devices or auxiliaries known to the art, and commonly employed in conjunction with a rotary ring or spokeless wheel excavator of this kind, can be employed if necessary or desirable.

50 What I claim as my invention is:

1. An excavator comprising a digging bucket, instrumentalities for operating said bucket, and means for causing the bucket to dump its load, said bucket having a 55 hinged gate at the rear end thereof, an element for holding the gate closed, and stationary means for operating said element to unlock the gate, said instrumentalities including a rotating ring, said element being 60 pivoted on said ring, said gate being formed with a slot to receive said ring, and said slot having its inner end provided with means to interlock with said element.

2. An excavator comprising a digging 65 bucket, instrumentalities for operating said

bucket, and means for causing the bucket to dump its load, said bucket having a hinged gate at the rear end thereof, an element for holding the gate closed, and stationary means for operating said element to unlock the gate, said element being in the form of a pivoted catch having a lug for engaging said means, and said instrumentalities including a ring having walls spaced apart to accommodate said catch between 70 them. 75

3. An excavator comprising a digging bucket, instrumentalities for operating said bucket, and means for causing the bucket to dump its load, said bucket having a hinged gate at the rear end thereof, an element for holding the gate closed, forming a stop to limit the closing movement of the gate, and stationary means for operating said element to unlock the gate, said element being pivoted between its ends to tilt about a horizontal axis, both ends of said element being shaped to engage said gate, and the hinge for said gate being at the heel of the bucket. 80 85

4. An excavator comprising a digging bucket, instrumentalities for operating said bucket, and means for causing the bucket to dump its load, said bucket having a hinged gate at the rear end thereof, an element for holding the gate closed, and stationary means for operating said element to unlock the gate, said bucket having a central vertical wall, and said element being pivoted directly behind said wall. 90 95

5. An excavator comprising a digging bucket, instrumentalities for operating said bucket, and means for causing the bucket to dump its load, said bucket having a hinged gate at the rear end thereof, an element for holding the gate closed, and stationary means for operating said element to unlock the gate, a pair of cleaners disposed in position to pass through the bucket, and said element being pivoted in position to 100 pass between said cleaners. 105

6. An excavator comprising a digging bucket, instrumentalities for operating said bucket, and means for causing the bucket to dump its load, said bucket having a hinged gate at the rear end thereof, an element for holding the gate closed, and stationary means for operating said element to unlock the gate, said instrumentalities including a rotating ring, said element being 110 pivoted on said ring, said gate being formed with a slot to receive said ring, and said slot having its inner end provided with means to interlock with said element, a cleaner disposed in position to pass through said bucket, the hinge for said gate being at 115 the heel of the bucket. 120

7. An excavator comprising a digging bucket, instrumentalities for operating said bucket, and means for causing the bucket 125 130

to dump its load, said bucket having a hinged gate at the rear end thereof, an element for holding the gate closed, and stationary means for operating said element to 5 unlock the gate, said element being in the form of a pivoted catch having a lug for engaging said means, and said instrumentalities including a ring having walls spaced apart to accommodate said catch between 10 them, said bucket having a portion secured

between said walls, and a pair of cleaners disposed in position to pass through the bucket at opposite sides of said ring.

Signed by me at Chicago, Illinois, this 20th day of March, 1915.

JAMES C. FRENCH.
